UNITED STATES PATENT OFFICE.

ALBERT L. SHIDLER AND HERMAN H. MOOTZ, OF SIOUX CITY, IOWA.

AUTOMOBILE TRUNK AND LUGGAGE CARRIER.

Application filed January 7, 1927. Serial No. 159,710.

This invention relates to luggage carriers for automobiles and pertains particularly to an improved trunk structure.

The primary object of this invention is 5 to provide, in a manner as hereinafter set forth, a luggage trunk for automobiles having means whereby the carrying capacity of the same may be increased.

The invention contemplates the provision 10 of a trunk structure made up into two sections one telescoping into the other, one of the sections being designed to be secured in position on the vehicle while the other section is retained in shiftable relation to the fixed 15 section. A hinged lid is provided which closes the top portion of the trunk structure when the sections are telescoped together and may be locked in closed position in the usual manner.

20 Another object of this invention is to provide a trunk designed to be enlarged in the manner described, which will be strong and durable, of neat and attractive appearance and comparatively inexpensive to manufac- 25 ture.

Numerous other objects and advantages of this invention will become apparent as the description of the same proceeds, and the invention will be best understood from a consideration 30 of the following detailed description taken in connection with the accompanying drawings forming a part of this specification, with the understanding, however, that the invention is not confined to any strict 35 conformity with the showing of the drawings, but that the same may be changed or modified so long as such changes or modifications mark no material departure from the salient features of the invention, as expressed 40 in the appended claims.

In the drawings:

Figure 1 shows the trunk structure embodying this invention in front elevation.

Figure 2 is a top plan view of the same 45 with the top raised and the shiftable portion of the trunk extended.

Figure 3 shows the trunk structure in side elevation the opened-up position being indicated in dotted lines.

50 Figure 4 is a vertical section taken substantially upon the line 4—4 of Figure 2.

Figure 5 is an enlarged transverse section through the central portion of the trunk bottom showing the manner in which the sections are secured together in closed position.

55 Figure 6 is an enlarged transverse section

through the bottom of the closed trunk structure showing guide means between the two sections.

Figure 7 is a section taken substantially 60 upon the line 7—7 of Figure 2.

Referring now to the drawings in detail wherein like numerals of reference indicate corresponding parts throughout the several views, the invention comprises two body sections 1 and 2, and section 1 comprising the main body portion of the trunk structure which is designed to be secured permanently to the motor vehicle upon which the trunk is to be carried. This section 1 comprises the 65 back and end walls 3 and 4 respectively and the bottom wall 5 and the end walls 4 have their top edges inclined from the rear to the forward portion thereof, as is shown in Figures 3 and 4.

Secured to the top edge of the back wall 3 is the back portion of the lid 6, which as is shown, is hinged to the back wall to swing upwardly therefrom and which has the lower edges of the end walls 7 thereof inclined to 70 conform to the inclination of the body end walls 4, so that when the lid is closed, the top of the trunk will be level as shown in Figure 3. The front of the section 1 is open as 75 shown, and secured across the inner face of each end wall 4 at the top thereof there is formed a downwardly extending guide flange 8 which is in spaced parallel relation with the wall 4 upon which it is carried.

The bottom wall 5 of the section 1 is provided with transverse depressions 9 which constitute guide ways extending from the forward edge of the bottom to the back wall, the purpose of which will be hereinafter set forth.

90 The section 2 of the trunk is shiftable with respect to the section 1 and is of such size as to permit its being snugly projected into the open front of the section 1, the front and end walls 10 and 11 of the shiftable section 2 being 95 of the same height as the forward edge of the end walls 4 of the section 1.

The top edge of each end wall 10 of the section 2 is turned over to provide a bead 12 which is positioned in the channel formed 100 between the guide flange 8 and the adjacent end wall, at each end of the section 1 and a tongue 13 is formed at the lower edge of each bead 12 at the inner end, which tongues engage in a catch member 14 formed at the outer end, and lower edge, of each of the guide flanges 8 to prevent the section 2 being en- 110

tirely withdrawn from the section 1, as will be readily understood upon the reference to Figure 4. As will also be seen upon reference to this figure the rear of the section 2 is open and the bottom 15 rests and slides upon the bottom 5 of the fixed section.

Secured vertically against the inner face of the wall 11, of the section 2 is a pair of spaced reinforcing beams 16 which extend through the floor 15 of this section and connect with the outer ends of guide bars 17 secured transversely of and in spaced parallel relation upon, the under face of the bottom, these bars being designed to fit in the grooves

15 9 formed in the bottom of the section 1.

In the central portion of the bottom 5 of the section 1 adjacent the front and rear portions thereof are formed apertures 18 and secured to the central portion of the bottom 15 of the 20 section 2 is a spring controlled catch member 19, the tongue portion 20 of which is adapted for selective engagement in either of the apertures 18. By this means the sections can be latched in opened or closed position.

25 Means is provided in the form of a thumb screw 21 threaded through each end wall 4 of the section 1, for binding the bead 12 against the guide flange 8 to secure the sections in any desired position, independently of the latch 30 element 19.

Upon the front wall 11 of the trunk section 2, racks 22 are secured to provide a tire carrier, the carrier being shiftable with the section 2 of the trunk, as will be readily understood.

35 From the foregoing description, it will be seen that the structure embodying this invention will be particularly useful to persons traveling or to drummers who must carry 40 quantities of material with them, as the carrying space can be readily increased or decreased in size to accommodate the quantity of material to be carried.

Having thus described our invention, what 45 we claim is:

1. An automobile trunk comprising a main section having an open front, an auxiliary section slidably associated with the first section to be extended through the open front 50 thereof and a lid hinged to the main section of an area to close the main section but not the auxiliary section when the latter is extended.

2. A combination trunk and luggage carrier comprising a main section having guide flanges at the top thereof and guide ways in the bottom thereof, an auxiliary section having certain edge portions slidably related with said guide flanges so that said auxiliary 60 section may be extended horizontally of said main section, guide bars carried by the auxiliary section for sliding movement in guide ways, a lid hinged to the main section for closing the same and a pair of lock devices, 65 one associated with said flanges and the other

associated with the bottom of said sections whereby the sections may be locked in either of their two adjusted positions.

3. In an automobile trunk, a main section having an open front, an auxiliary section 70 telescoping therein and movable out through the open front, means for limiting the outward movement, a tire rack secured on the outer wall of the auxiliary section to be moved therewith from one vertical position to another to be readily accessible, and a cover hinged to and covering said main section, but terminating short of the fully extended auxiliary section.

4. A combined automobile trunk and luggage carrier comprising a stationary section adapted to be mounted on an automobile and having side walls, a bottom wall, a rear wall having a lid hinged thereto, and an open front; a movable section including a vertical 80 front wall member adapted to close the open front of said stationary section to form a trunk, and means connecting said front wall member with said stationary section to allow said front wall member to move outwardly 85 away from said stationary section while remaining constantly in a vertical position to form a luggage carrier.

5. A combined automobile trunk and luggage carrier comprising a stationary section 90 adapted to be mounted on an automobile and having side walls, a bottom wall, a rear wall having a lid hinged thereto, and an open front, a movable section including a vertical front wall member adapted to close the open 95 front of said stationary section to form a trunk, a tire carrier mounted on said front wall, and means connecting said front wall member with said stationary section to allow said front wall member to move outwardly 100 away from said stationary section while remaining constantly in a vertical position to form a luggage carrier.

6. A combined automobile trunk and luggage carrier comprising a stationary section 110 adapted to be mounted on an automobile and having side walls, a bottom wall, a rear wall, and an open front, a movable section including a vertical front wall member adapted to close the open front of said stationary section to form a trunk a lid therefor, a tire carrier mounted on said front wall and movable with said movable section, and means connecting said front wall member with said stationary section to allow said front wall member to move outwardly 115 away from said stationary section while remaining constantly in a vertical position to form a luggage carrier.

7. A combination trunk and luggage carrier comprising a main section having guide flanges at the top thereof and guide ways in the bottom thereof, an auxiliary section having certain edge portions slidably related with said guide flanges so that said auxiliary 120 section may be extended horizontally of said main section, guide bars carried by the auxiliary section for sliding movement in guide ways, a lid hinged to the main section for closing the same and a pair of lock devices, 125 one associated with said flanges and the other

main section, guide bars carried by the auxiliary section for sliding movement in the guide ways, a lid for closing said main section, said auxiliary section having a vertical front wall member adapted to move outwardly away from said main section while remaining constantly in a vertical position to form a luggage carrier, and a tire carrier mounted on said vertical front wall member movable therewith and remaining constantly 10 in a vertical position.

In testimony whereof we affix our signatures.

ALBERT L. SHIDLER.
HERMAN H. MOOTZ.
